UNITED STATES PATENT OFFICE.

WILLIAM HJALMAR LINDQUIST, OF BAYONNE, NEW JERSEY.

REFRIGERATING APPARATUS.

Application filed February 17, 1922. Serial No. 537,201.

To all whom it may concern:

Be it known that I, WILLIAM HJALMAR LINDQUIST, a citizen of the United States, residing at Bayonne, county of Hudson, and 5 State of New Jersey, have invented certain new and useful Improvements in Refrigerating Apparatus, fully described and represented in the following specification and the accompanying drawings, forming a part of 10 the same.

This invention relates to refrigerating apparatus and more particularly to that type of refrigerator adapted for household use.

I am aware that many machines have been 15 designed purporting to meet the requirements of the small consumer but such machines have been so designed and constructed as to necessitate the employment of numerous mechanical parts, comparatively 20 complicated piping arrangement and a plurality of valves. Machines as heretofore constituted may have proved entirely efficient when tended by an expert operator or engineer. It is obvious however that an apparatus intended for domestic use must be 25 constructed to give efficient service and at the same time avoid relatively complicated mechanism which may demand the exercise of more than ordinary skill on the part of 30 the operator.

My invention therefore contemplates an apparatus constructed with a view to simplicity and one in which the various elements are so arranged and associated as to bring the management of the apparatus 35 within the range of ability of a person possessing ordinary intelligence although lacking in technical knowledge pertaining to refrigeration.

40 Refrigerating apparatus of the character to which my invention relates employs a compressor in which a lubricant such as glycerine is used. Great difficulty has heretofore been experienced in preventing this lubricant from entering the system.

I overcome the above mentioned difficulty, 45 in my apparatus, by an improved type of separator which permits the gas to pass into the condenser but arrests the progress of the lubricant and effects its removal or return to the compressor.

Another important feature of my apparatus is the disposition of a check valve in the line of circulation and between the 50 expansion chamber and the compressor.

The employment of the said valve prevents the lubricant from backing into the expansion chamber when the apparatus is shut down and a pressure exists in the condenser.

By the embodiment of the above mentioned and other features together with the elimination of valves and the simplicity of construction of my device an apparatus is provided which will operate in an efficient and practical manner at a very low maintenance cost. 60 65

In tests made by an apparatus constructed according to my invention I have found that a minimum amount of personal attention is necessary and any that may be required is of a nature within the ability of 70 the average individual.

An object of my invention, is therefore, to provide an apparatus of the above mentioned character which is of a simple construction and adapted for domestic use and 75 household service.

Another object is to provide an apparatus in which lubricant or other foreign matter is prevented from entering the condenser 80 or refrigerating system.

The above mentioned and other objects will be apparent from the following description and by reference to the accompanying drawings in which: 85

Fig. 1 is a fragmentary view of my apparatus taken in vertical section, through the supporting structure, the condenser, expansion valve and expansion chamber.

Fig. 2 is an external elevational view of 90 a refrigerator embodying my invention.

Fig. 3 is a sectional view of the apparatus taken on line III—III indicated in Fig. 1.

Fig. 4 is a transverse section of the separator taken on line IV—IV in Fig. 3. 95

Fig. 5 is a transverse section of the separator taken on line V—V in Fig. 3, and Fig. 6 is a transverse section of the separator taken on line VI—VI in Fig. 3.

My apparatus comprises the usual elements necessary to effect refrigeration by means of absorption through the employment of any suitable volatile medium as ethyl-chloride or the like. 100

In addition to the necessary condenser, 105 compressor and expansion chamber, I provide a separator by means of which any lubricant carried by vapor is returned to the compressor. Between the expansion chamber and the compressor I provide means 110

to prevent lubricant from entering the said chamber.

Referring now to the drawing, the apparatus illustrated as one embodiment of my invention includes a compressor, indicated, as a whole by the numeral 5, a condenser 6, an expansion valve 7, (see Fig. 1) and a grid or expansion chamber 8. These elements are suitably supported by a refrigerator structure indicated as a whole by the numeral 9 and which may be of suitable proportions for household use.

A refrigerating compartment may be disposed adjacent the expansion chamber and thereby be cooled by absorption of heat therefrom by the brine from which the heat is in turn absorbed during the vaporization of the fluid in the expansion chamber.

The grid 8 which constitutes the container for the volatile liquid consists of upper and lower horizontal headers 14 and 15 respectively. These headers are connected by vertical tubular members 16. The upper header is provided with an outlet 17 for the passage of the vapor through pipe 18. (See Fig. 3.) The vapor passes through a check valve 19 when the compressor 5 is actuated and thence into an oil and gas separating chamber 21 and into the condenser 6. The purpose of the chamber 21 will be hereinafter more fully described.

In the present invention air is employed as the cooling medium for condensing the vapor and any suitable means may be utilized to effect the mechanical circulation of air about the condenser tubes or a natural circulation may be used.

In the drawing a fan 22 is employed for the mechanical circulation of air. This fan is secured to a shaft 20 carried in a bracket 22', and is provided with a pulley 23. The fan may be driven by any suitable source of power and as illustrated it is connected by a belt 23' to a pulley on the shaft 24' of a motor 24, which motor also drives a rotary member in the compressor 5. It will be appreciated that considerable advantage is derived by utilizing a single motor for the two above mentioned purposes and that the initial and maintenance cost of the apparatus is decreased and that economy of space is attained. After the vapor has been condensed the condensate or liquid flows into the expansion or float-valve 7 which is provided with an aperture or outlet 25 through which the liquid may pass into a supplemental passage 26 and thence through pipe 27 and into a lower inlet 28 of the grid 8 thus making a complete cycle.

The grid 8 is preferably enclosed in a casing or tank 29 which may contain any suitable heat conducting medium, brine being preferable, a suitable inlet 30 being provided for its introduction. If desirable a plurality of chambers 31 may be disposed

within the casing and in contact with the brine on three sides thereof. The front or ends being provided with a suitable refrigerator door to permit the disposition of water pans 32 within the chambers 31 for the production of a supply of ice for table or other use.

Referring to the compressor 5, a compressor of any suitable type may be employed to act as a heat pump to cause the heat carrying fluid to pass off into the condenser.

The compressor for this purpose is of a well known type and as shown in the drawing may be briefly described as comprising a casing 35 having a cylindrical bore 36 in which the shaft 24' is disposed. A cylindrical member 37 is secured to the shaft eccentrically and positioned about the said member is an annulus 38 in which radially reciprocable blades 39 are disposed and adapted to make contact with the wall of the casing 35. The blades are maintained in contact with the casing throughout their movement by the engagement of their inner ends with the member 37. As the shaft rotates, the blades, in cooperation with the wall of the casing, form pockets which carry successive sections of vapor and discharge them into the separator chamber.

In a compressor of this character it is necessary, in order to provide an efficient seal, to fill the casing with a lubricant such as glycerine or other viscous substance and it has been found difficult to keep this lubricant from entering the condenser.

When lubricant is permitted to enter the system the various passages finally become choked preventing the necessary free circulation of fluid.

It is an advantage therefore to provide a means for separating the lubricant from the vapor, prior to its delivery to the condenser by the compressor. In the present invention a separator is provided comprising the chamber 21 in which an axially disposed tubular member 41 is provided and connected with the compressor by a nipple 42 which affords communication for the vapor from the expansion chamber to the said member which is provided with a plurality of apertures 43 for the passage of the vapor into the chamber 21.

The vapor after passing into member 41 is discharged through the apertures 43 which, owing to their relatively small perimeters, effect an increase in the velocity of the vapor. Thus the discharged vapor is projected or sprayed into the chamber 21 and the heavier particles of the lubricant carried by the vapor are precipitated to the bottom of the chamber by virtue of their potential energy. In this manner a very effective separation of the gaseous and viscous fluid is produced. It will be under-

stood that the combined areas of the apertures 43 is less than the internal cross sectional area of the member 41. A more complete separation may, however, be produced by the proper disposition of a plurality of annular baffle-plates 44 which are arranged around the member 41 and in the path of the discharged fluid. Thus an impingement of the fluid upon the baffle-plates is effected, and the heavier particles of the lubricant momentarily adhere to the plates and then fall to the lower portion of the chamber and are led to the compressor by a by-pass in the form of a pipe 45.

15 The initial filling of lubricant necessary for the operation of the compressor is introduced through an aperture in the side of the chamber upon the removal of a screw plug 46 and the lubricant enters the compressor through the by-pass 45.

20 The chamber 21 is divided into two compartments by a transverse partition 47 which also constitutes the upper portion of the tubular member 41. This partition is provided with apertures 48 through which the vapor passes and thence through an outlet 49 and into the condenser. As an added impedance to any particles of lubricant which may enter the upper compartment of the chamber 11, I provide a screen or filter 51 in the outlet 49.

25 It will be appreciated that my separator not only provides a tortuous passage for the vapor, intermediate the compressor and the condenser, but also provides means for accelerating the movement of the gases by virtue of the restricted outlets 43 from the member 41 into the chamber 11. An elimination of such matter as would otherwise 30 cause a decrease in the efficiency of the condenser tubes is produced.

35 When the machine has been shut down, after operation, a pressure exists in the condenser which tends to force the lubricant through the pipe 18 and into the expansion chamber with the result that each termination of operation a deposit of viscous substance enters the chamber and in time 40 renders it inoperative for efficient circulation. In order to avoid this disadvantage I provide means in the form of a check valve 19.

45 The condensate which forms in the condenser is controlled by the float or regulator valve 7 which comprises a casing 52 in which is disposed a float 53 having an arm 54 pivoted in the usual manner on pin 54'. The arm is provided with a stem 56 which seats upon and closes the aperture 55 when the liquid in the casing 52 is below a given level.

50 When the liquid rises the float moves upwardly and the stem 56 raises and opens the valve to permit a flow of liquid through 55 the pipe 27 and into the expansion chamber.

Although the float valve illustrated may be of any given construction I may provide a suitable chamber 57 incorporated therewith, for the more convenient initial introduction of the volatile liquid employed in the system. This liquid as for instance, ethyl-chloride is led into the chamber 57 through an aperture 58 which is normally closed by a screw plug 59. The liquid then passes through the pipe 27 and into the expansion chamber.

55 It will be understood that during the introduction of the initial supply of liquid to the system that no liquid is contained in the casing 52 and that the aperture 25 is closed.

60 By the provision of the chamber 57 it is more convenient to introduce a liquid to the system, furthermore, I provide the chamber with a pocket 61 which serves as a trap to collect any particles of foreign matter that may be contained in the condensate as it flows to the expansion chamber 8 during the operation of the machine.

65 In practice a volatile fluid such as ethyl-chloride or the like is introduced into the expansion chamber through the aperture 58. The chamber 57 serves as a mouth or flared inlet to the pipe 27 through which the fluid enters the grid 8. A sufficient amount of fluid is provided to maintain a given level in the grid. The aperture is then closed by the plug 59. A lubricant may then be supplied to the compressor through an aperture in the chamber 11, upon the removal of the plug 46. A given amount of lubricant is introduced and led to the compressor through the pipe connection 45, the plug 46 is then replaced. The tank 29 may then be filled with brine 105 through the inlet 30.

70 The system having been charged, the motor 24 is started and the compressor creates a vacuum in the grid 8 causing a rapid volatilization of the refrigerant. The 110 usual physical actions then follow, namely the volatilization of the fluid effects an absorption of heat from the brine which in turn absorbs heat from its environment which includes the chamber constituting 115 the refrigerator.

75 The volatilized fluid or vapor passing through the compressor carries minute quantities of lubricant. This vapor upon entering the tubular member 41 within the 120 separator chamber 11 is discharged through the restricted apertures in said member and consequently the rate of flow of the vapor is increased to such velocity that it strikes the baffle-plates which serve to overcome 125 the inertia of the particles of lubricant which then fall to the lower quiescent portion of the chamber. The vapor, however, resumes its passage upwardly and enters 130 the condenser, while the removed lubricant

combines with the lubricant in the lower portion of the chamber 21 and finally enters the compressor through the by-pass 45.

The vapor having passed into the condenser is cooled and liquified either by a natural circulation of air or by the mechanical circulation of air distributed by the fan 22.

The condensate or liquid flows into the casing 52 of the float valve 7 until a sufficient accumulation of liquid causes the float 53 to rise permitting the liquid to escape through the aperture 25 from whence it passes through the chamber 57 via pipe 27 and into the grid 8 which completes the cycle necessary for continuous refrigeration.

The recess or pocket 61 in the chamber 57 serves to entrap such particles of foreign matter as may be contained in the condensate as it passes through the chamber 57.

It will be noticed that my apparatus is unique in its absence of valves other than the check valve and float valve. No hand valves are included and an important feature of my invention resides in the elimination of hand valves which, in an apparatus for domestic use, constitute a source of uncertainty in the mind of an inexperienced operator. Furthermore where hand valves are employed there is always a tendency on the part of the layman to manipulate such valves experimentally to the detriment of continuous or efficient operation of the apparatus.

Although my invention has been shown and described in its preferred form, it will be understood that various changes may be made in the arrangement and details of the various parts constituting the complete apparatus without departing from the invention and it is to be understood that all such changes and modifications may be made

without departing from the spirit and scope of the appended claims.

What is claimed is:

1. A refrigerating apparatus having an upper and lower compartment, a condenser comprising a continuous tube disposed in coiled formation about the inner walls of said upper compartment, a compressor element, a separator element positioned above and in communication with said compressor element, said separator also being in communication with said condenser, a check valve laterally disposed with respect to said compressor and in communication therewith, a motor for driving said compressor, said compressor, separator, valve and motor being disposed within said condenser coil, and an expansion chamber in said lower compartment and in communication with said compressor.

2. A refrigerating apparatus having an upper and lower compartment, a condenser comprising a continuous tube disposed in coiled formation about the inner walls of said upper compartment, a compressor element, a separator element positioned above and in communication with said compressor element, said separator element also being in communication with said condenser, a check valve laterally disposed with respect to said compressor and in communication therewith, a motor for driving said compressor, and a fan for causing a circulation of air, connection between said fan and said motor to drive the former, said compressor separator, valve, motor and fan being disposed within said condenser coil and an expansion chamber in said lower compartment and in communication with said compressor.

In testimony whereof I have hereunto set my hand.

WILLIAM HJALMAR LINDQUIST.
